UNITED STATES PATENT OFFICE.

CHARLES F. SPARKS, OF ST. LOUIS, MISSOURI.

CALCINING METHOD AND APPARATUS.

Application filed June 12, 1922. Serial No. 567,855.

To all whom it may concern:

Be it known that I, CHARLES F. SPARKS, a citizen of the United States, residing in the city of St. Louis and State of Missouri, have invented new and useful Improvements in Calcining Methods and Apparatus, of which the following is a specification.

This invention relates to calcining methods and calcining apparatus, and the general object of the invention is to provide a simple method and means for effecting the calcining operation in such a way as to enable the heating medium to be brought into close contact with the material being calcined; also to provide means for effecting the cooling of the material, if desired, before removing the same from the calcining chamber. A further object is to provide apparatus which can be controlled in operation so as to insure that the material will be subjected to the desired temperature for any desired length of time.

Further objects of the invention will appear hereinafter.

The invention consists in the novel features, and in the general combination of parts to be particularly described hereinafter, all of which contribute to produce a simple and efficient calcining apparatus. A preferred embodiment of my invention will be particularly described in the following specification, while the broad scope of my invention will be pointed out in the appended claims.

The invention also resides in the novel steps and combination of steps involved in my novel method, all of which will be described in the following specification and set forth in the claims upon the method.

In the drawing—

Figure 1 is a side elevation and partial section of my novel apparatus, by means of which my method may be practiced;

Figure 2 is a cross-section taken about on the line 2—2 of Figure 1.

In practicing my method, I advance a mass of the material to be calcined through the calcining chamber, and I obstruct the path of the same at a plurality of points on lines passing transversely through the mass, thereby forming ducts at the obstructed points; the walls of these ducts are formed partly in the material being calcined; I then pass a heating medium through the ducts and in direct contact with the material to be calcined. In this way,

the heat is very effectively and efficiently applied for my purposes.

I prefer to obstruct the movement of the material at three separated points on transverse lines disposed apart along the line of movement of the material so as to produce three transverse ducts in the material at the obstructed points; I then pass a heating medium, such as hot air or gas, at a relatively low temperature through the duct which is adjacent to the first obstructed point, and I pass a heating medium at a relatively high temperature through the second duct which is reached by the material in its movement. In this way, the material is first subjected to the relatively low temperature and then to the relatively high temperature. Through the third duct, I pass a cooling medium which reduces the temperature of the material so that it can be removed from the calcining chamber at any desired temperature. I shall now describe my novel apparatus which is well adapted for carrying out my method.

This apparatus is very simple and comprises a calcining chamber 1 which may be provided with a hopper 2 above so as to enable the material to be calcined, for example, fuller's earth, to be introduced into the calcining chamber from above. The side wall of the chamber near the bottom may be provided with flap doors 3 through which the calcined material may be removed, thereby enabling the material above to advance or move downwardly by gravity through the calcining chamber.

In order to obstruct the movement of the calcining material at a plurality of points, I provide a plurality of sheds 4^a, 4^b and 4^c. These sheds are constructed so that they extend transversely across the path of the material as it descends, and are so constructed that they co-operate with the material to produce ducts in the spaces under the sheds. I prefer to construct these sheds of angle iron with the apex of the angle disposed upwardly, the flanges of the angle being disposed on an angle of 45° in each direction so as to shed the material in both ways. It being understood that the material completely fills the chamber and hopper, it will be evident that the material tends to flow in under the sheds so that under each shed, a large part of the wall of the duct 6 is composed of the material. I prefer to arrange the sheds 4^a, 4^b, 4^c in vertical sets

and for the purpose of illustration, I have shown three such sets (see Figure 2). The sheds of the two outside vertical rows are disposed in a staggered relation with respect to the middle vertical row. It should be understood however, that each vertical row operates substantially as a unit, and the number of units employed would be determined by the desired capacity for the calcining chamber. As the material comes down, it comes in contact first, with the shed 4^a and then with the shed 4^b and at last with the shed 4^c.

According to my invention, I provide means for passing a heating medium through the duct 6 under the shed 4^a which is at a relatively low temperature as compared with the heating medium which I pass through the corresponding duct under the shed 4^b. In this way, I subject the material first, to a relatively low temperature and then to a relatively high temperature. In practice, I accomplish this by providing a gas-burner 7 or other suitable means for introducing a heating medium. In the present instance, the end walls 8 of the calcining chamber are provided with triangular openings 9 which receive the ends of the sheds. The flame at the gas jet 7 entrains air at the adjacent end of the duct 6, and a relatively high temperature is produced in the mixed hot air and gases of combustion as they pass toward the other end of the duct under the shed 4^b. The space under the shed 4^b is connected with the space under the shed 4^a so that after traversing the duct under the shed 4^b the heating medium passes up and into the space under the shed 4^a. In order to accomplish this, I prefer to connect the openings 9 corresponding to these two sheds by a bonnet 10 (see Figure 1). In this way, after parting with a large part of their heat, the hot gases and air pass back under the shed 4^a, and thence, pass out to the atmosphere through the wall of the chamber.

While I have illustrated a single duct or pass for the hottest gases and a single duct or pass for the return of the same after they have lost a part of their heat, it should be understood that, if desired, I may pass and repass these gases as often as necessary; the practice as to this would depend upon the peculiar nature of the calcining problem and also upon the kind of material being treated.

I prefer to provide means for effecting the cooling of the calcining material before removing it from the calcining chamber, and for this purpose, the aforesaid lower shed 4^c is provided. If desired, a cooling medium may be sent through the duct 6 under this shed, but under most circumstances sufficient cooling effect will result if the ends of this duct are simply left open

to the atmosphere by extending the sheds to the openings 9 in the end walls of the chamber.

In the calcining or tempering of fuller's earth, it is desirable to know with substantial accuracy just how long the earth has been subjected to a certain temperature. My method and apparatus is admirably adapted for attaining this result in operation. In order to accomplish this, I provide the side walls at any desired points with openings 11 provided with flap doors 12, and at these openings, I provide small tubes which extend into the interior of the chamber. In these tubes, I may insert thermometers which will indicate the temperature in the vicinity of the upper and lower sheds 4^a and 4^b. By observing these thermometers, the operator of the apparatus may be intelligently guided in the regulation of the temperature of the heated medium which is admitted to the heating ducts under the sheds 4^a and 4^b. And by withdrawing the calcining material at a certain rate, it can readily be calculated just what length of time the material has spent in passing through zones of different temperature. In this way, it becomes possible for the operator of this apparatus to certify positively as to the length of time the earth was subjected to a certain temperature or certain temperature limits.

The use of angle irons to construct the sheds is advantageous because this shape produces a channel on the underside of the shed so that the space under the sheds operates as a flue to guide the hot gases.

While a large part of the calcining effect is produced by subjecting the material to direct contact with the heated medium, of course, considerable calcining effect is derived from the high temperature of the metal of the sheds. Of course, the sheds will come in direct contact with a large amount of the material as it moves down the calcining chamber. It is desirable of course, that they should be constructed of heat-conducting material such as steel or iron.

It is understood that the embodiment of the invention described herein is only one of the many embodiments my invention may take, and I do not wish to be limited in the practice of my invention nor in my claims, to the particular embodiment set forth.

Although I have only illustrated two openings 11 for thermometers, if desired, I may provide a similar opening about on the level with the lower sheds 4^c so as to indicate the temperature of withdrawal of the calcined material.

What I claim is:—

1. In calcining apparatus, the combination of a calcining chamber having a lower outlet for withdrawing the calcined mate-

rial, a transversely disposed bar extending through the chamber and presenting a channel on its underside to receive the heating medium at a relatively high temperature, 5 and enable the same to come in direct contact with the material within the calcining chamber, a second transversely disposed bar at a higher level than the lower bar and presenting a channel on its underside, means 10 for connecting the two bars so as to enable the heating medium to pass from the channel of the lower bar into the channel of the upper bar, and an angle bar extending transversely through the chamber below 15 said first named bar and having a channel on its underside, the ends of said channel extending through the walls of the chamber and enabling a cooling medium to pass through the same and come in direct contact 20 with the material below the bar.

2. In a calcining apparatus, the combination of a calcining chamber constructed to be charged from above and having an outlet below for withdrawing the calcined material, 25 a transversely disposed bar of heat-conducting material extending through the

chamber and presenting a channel on its underside to receive the heating medium at a relatively high temperature, and enable the same to come in direct contact with the material within the calcining chamber, a second transversely disposed bar at a higher level than the lower bar also constructed of heat-conducting material and presenting a channel on its underside, means for connecting the two bars so as to enable the heating medium to pass from the channel of the lower bar into the channel of the upper bar, and a third angle bar extending transversely through said chamber below the level of the 30 first named bar and having a channel on its underside, and co-operating with the calcining material to form a duct therethrough, the ends of said channel extending through the walls of the chamber and enabling a 35 cooling medium to pass through the same and come in direct contact with the material below the bar. 40

In testimony whereof, I have hereunto set my hand.

CHARLES F. SPARKS.
